TOILETRY RECEPACLE

Franklin S. Briles, Rolling Hills, Calif., assignor to Franklin S. Briles, Inc., El Segundo, Calif., a corporation of California

Filed Mar. 17, 1965, Ser. No. 84,339

Term of patent 14 years

(Cl. D4—3)

FIG. 2

FIG. 3

FIG. 4FIG. 5FIG. 6FIG. 7FIG. 1 is a perspective view of a toiletry receptacle, showing my new design;

FIG. 2 is a top plan view of the toiletry receptacle illustrated in FIG. 1;

FIG. 3 is a front elevational view of the toiletry receptacle;

FIG. 4 is a rear elevational view of the toiletry receptacle;

FIG. 5 is a bottom view of the toiletry receptacle;

FIG. 6 is a side elevational view of the toiletry receptacle taken from the right side;

FIG. 7 is a cross-sectional view of the toiletry receptacle taken on line 7-7 of FIG. 1.

I claim:

The ornamental design for a toiletry receptacle, as shown.
